UNITED STATES PATENT OFFICE

EARL A. REED, OF TULSA, OKLAHOMA

DRILL CUTTER

Original application filed May 26, 1927, Serial No. 194,315. Divided and this application filed July 26, 1928. Serial No. 295,389.

This invention relates to improvements in earth boring drills and forms a division of my copending application Serial No. 194,315, filed May 26, 1927.

5 The present invention relates more particularly to the frusto-conical type of cutter and the manner of mounting the same upon a bit head.

10 It is an object of my invention to provide a mounting for frusto-conical cutters which will afford a maximum bearing surface area and which at the same time will facilitate the removal and substitution of both the cutter and bearing elements.

15 Further objects relate to the construction and design of the parts with a view to simplifying and effecting economies in the manufacture and use thereof, as will more definitely appear from the following description and accompanying drawing.

Referring now to the several views of the drawing,

20 Figure 1 is a view partly in vertical section of a bit head having a pair of frusto-conical roller cutters mounted therein in accordance with the present invention,

Figure 2 is a top plan view of the cutter, and

25 Figure 3 is a top plan view of the conical bearing.

My present invention is shown in connection with a one piece drill head construction indicated generally by the reference character 1. This drill head is formed with a 30 pair of spaced, depending spindles or legs 2 on which the respective rotary cutters are mounted. The space 3 between the two spindles is just sufficient to accommodate the two rotary cutters in substantially abutting relation. The drill head is provided at its upper end with the usual threaded portion 4 which constitutes one part of a coupling member. The head is also provided with the usual water duct indicated at 5.

35 The two cutters and their mountings are identical, and I will therefore describe the details of but one thereof. The spindle 2 is formed with a frusto-conical surface which in transverse section presents two surface elements substantially at right angles to one another and the lower one of which is intended to lie substantially horizontally when the drill is in operation. Projecting downwardly from the lower horizontal surface of the spindle is an integral pin 12, the purpose 55 of which will be hereinafter pointed out. A bushing 7 is formed with an internal frusto-conical surface of such size as to snugly fit the frusto-conical surface of the spindle. This bushing also has a similarly 60 formed external bearing surface with which the internal frusto-conical surface of the roller cutter has bearing engagement. The internal surface of the cutter is formed as shown in Figure 2 with an annular groove 65 or channel 11 for the reception of the pin 12 heretofore mentioned and also of a second pin 13. These two pins pass through corresponding apertures 14 and 15 formed in the bushing member and engage the lateral 70 and bottom walls of the groove 11. As shown in Figure 1 the pins 12 and 13 are disposed substantially at right angles to each other and it will therefore be apparent that when such pins are engaged within the annular groove 11 it will be impossible for the cutter to be separated in an axial direction from the bushing and spindle. Obviously 75 the cutter and bushing elements could not be assembled in the relationship in which they 80 are shown in Figure 1 if both of pins 12 and 13 were rigidly formed on the spindle. For this reason one of such pins is so constructed and arranged as to be removably and adjustably associated with the spindle. In the embodiment illustrated the pin 13 is located in a transverse aperture 16 of the spindle 2 and this pin has provided in its outer end an internally screw-threaded bore which is 85 adapted to receive an externally screw-threaded spindle 18. The outer end of the bore 16 in the spindle is enlarged as indicated at 17 and this enlarged portion of the bore is internally threaded to cooperate with an externally threaded enlargement 19 90 formed on the bolt 18. The head 19 may be provided with any suitable formations for the reception of an operating tool of any desired form. It will thus be seen that the pin 13 is readily removable from its engage- 95

100

ment with the annular groove 11, aperture 14 and the bore 16 of the spindle and that this pin may be adjustably positioned within the last mentioned bore.

5 An important characteristic of the present invention is the right angular relation of the surface elements of the frusto-conical spindle. This is clearly represented in Fig. 1 wherein an axial section through the spindle 10 discloses truly vertical and horizontal surfaces. One advantage of this construction, which is common to this application and the application hereinabove referred to, is that the spindle supports the loads imposed upon 15 it in operation substantially entirely along vertical lines, thus subjecting the spindle only to compression stresses and substantially eliminating all leverage stresses. This 20 construction possesses an important added advantage in connection with the present invention in that it permits the use of a bushing of unitary construction. It should be apparent that it would be practically impossible to assemble a structure such as is herein 25 shown if the surface elements of the various frusto-conical members were not disposed in substantially right angular relation. However, by virtue of this right angular relationship of surface elements, it is a simple 30 matter to assemble the cutter and bushing with the spindle and integral locking pin by merely moving the cutter and bushing toward the spindle with the surfaces diametrically opposite the pin and aperture respectively, in sliding engagement. Thus, it is 35 possible to use a bushing of unitary construction and to receive the advantages of such 40 construction.

The construction as thus described is of particular utility in connection with drill heads and cutters of relatively small sizes since it affords a maximum bearing surface area and yet retains all of the advantages of 45 mountings adapted more particularly for larger drills, such for example as that shown in my copending application above referred to. However, the present invention may be utilized in connection with cutters and drill 50 heads of any desired size.

55 It is to be understood that the present invention is susceptible of some modification and is not necessarily limited to the precise details of construction herein shown and described. For example, the stud 12 might be 60 formed as a separate locking element and be carried freely in the aperture 15 of the bushing with its ends in engagement with an aperture in legs 2 and the annular groove in 65 the cutter 8 respectively. This and other detail alterations I regard as falling within the scope of my invention and for this reason it is my intention that this invention be unrestricted other than by the appended 70 claims.

I claim:

1. In a device of the character described, the combination with a drill head, of a frusto-conical spindle secured thereto, a bearing element having internal and external frusto-conical surfaces and a frusto-conical roller cutter having an internal frusto-conical surface, the internal surface of said bearing element being adapted for engagement with the frusto-conical spindle and the external 75 surface of said bearing element having engagement with the internal surface of said cutter and means projecting from said spindle thru said bearing element and into engagement with said cutter for maintaining said cutter, bearing and spindle in assembled relation said means terminating between the surfaces of the frusto-conical cutter.

2. In a device of the character described, a bearing member having an external frusto-conical bearing surface, a frusto-conical cutter having an internal frusto-conical bearing surface adapted for engagement with the external surface of said bearing member and means passing thru the frusto-conical portion 80 of said bearing member at spaced points and engaging said cutter for permitting relative rotation of said cutter and bearing member but preventing axial separation thereof.

3. In a device of the character described, a bearing member having an external frusto-conical bearing surface, a frusto-conical cutter having an internal frusto-conical bearing surface adapted for engagement with the external surface of said bearing member, the 90 internal frusto-conical surface of said cutter having an annular groove therein and said bearing member having apertures arranged in registration with said groove and pins 95 passing thru said apertures and into said groove, whereby to prevent axial separation of said cutter and bearing member while permitting relative rotation thereof.

4. In a device of the character described, the combination with a drill head, of a frusto-conical spindle secured thereto, a bearing element having internal and external frusto-conical surfaces and a frusto-conical roller cutter having an internal frusto-conical surface, the internal surface of said bearing element being adapted for engagement with the frusto-conical spindle and the external surface of said bearing element having engagement with the internal surface of said cutter, the internal surface of said cutter being 110 formed with an annular groove therein and said bearing element having spaced apertures in registration with said groove and means projecting from said spindle thru said apertures and into said groove for maintaining the several parts in assembled relation while permitting free rotation of the cutter.

5. In a device of the character described, the combination with a drill head, of a frusto-conical spindle secured thereto, a bearing ele-

ment having internal and external frusto-conical surfaces and a frusto-conical roller cutter having an internal frusto-conical surface, the internal surface of said bearing element being adapted for engagement with the frusto-conical spindle and the external surface of said bearing element having engagement with the internal surface of said cutter, the internal surface of said cutter being formed with an annular groove therein and said bearing element having spaced apertures in registration with said groove and means projecting from said spindle thru said apertures and into said groove for maintaining the several parts in assembled relation while permitting free rotation of the cutter, said means comprising a first pin fixed to said spindle and a second pin removably associated therewith.

6. In a device of the character described, the combination with a drill head, of a frusto-conical spindle secured thereto, a bearing element having internal and external frusto-conical surfaces and a frusto-conical roller cutter having an internal frusto-conical surface, the internal surface of said bearing element being adapted for engagement with the frusto-conical spindle and the external surface of said bearing element having engagement with the internal surface of said cutter, the internal surface of said cutter being formed with an annular groove therein and said bearing element having spaced apertures in registration with said groove and means projecting from said spindle thru said apertures and into said groove for maintaining the several parts in assembled relation while permitting free rotation of the cutter, said means comprising a first pin formed integral with said spindle, said spindle having a bore therein arranged substantially at right angles to the axis of said pin and a second pin disposed in said bore and removably and adjustably associated with said spindle and adapted to be projected beyond the surface thereof and into engagement with one of said apertures and said groove, said second pin having an internally screw-threaded bore in the outer end thereof and a plug having screw-threaded engagement with the bore of said spindle and having an externally threaded shank for engagement with the threaded bore of said pin.

10. In a device of the character described, the combination with a supporting member having a frusto-conical external surface which in axial section presents right angularly disposed surface elements, of a member to be rotatably supported thereby and having a correspondingly formed internal surface, a pin projecting at right angles to the surface of said supporting member and adapted to engage an annular channel formed in the said frusto-conical internal surface and a second pin removably associated with said supporting member and likewise adapted to engage in said annular channel, whereby to prevent separation of said members.

11. A roller boring drill head composed of a single piece including two integral downwardly projecting legs diametrically opposite each other, frusto-conical spindles formed on said legs and whose axes are inclined downwardly and inwardly and whose surface elements are approximately at right angles to each other so that the lowermost portion thereof forms a line approximately horizontal to the vertical axis of the bit head while the innermost portion thereof forms a line approximately parallel with the vertical axis of the bit head, a locking element projecting downward from the surface of each of said spindles, and each of said spindles having a lateral aperture, a removable locking device carried in each said aperture and adapted to be projected beyond the surface of the spindle, bushings having frusto-conical internal and external surfaces and adapted for engagement with said spindles, said bushings having apertures through which said locking elements are adapted to project and frusto-conical roller cutters each having an internal frusto-conical surface for

7. A structure substantially in accordance with claim 5 and wherein said pins extend substantially at right angles to the surface of said spindle.

8. A structure substantially in accordance with claim 5 and wherein said pins are arranged substantially at right angles to each other and each said pin extends substantially at right angles to the surface of said spindle.

9. In a device of the character described, the combination with a drill head, of a frusto-conical spindle secured thereto, a bearing element having internal and external frusto-conical surfaces and a frusto-conical roller cutter having an internal frusto-conical surface, the internal surface of said bearing element being adapted for engagement with the frusto-conical spindle and the external surface of

face of said bearing element having engagement with the internal surface of said cutter, the internal surface of said cutter being formed with an annular groove therein and said bearing element having spaced apertures in registration with said groove and means projecting from said spindle thru said apertures and into said groove for maintaining the several parts in assembled relation while permitting free rotation of the cutter, said means comprising a first pin formed integral with said spindle, said spindle having a bore therein arranged substantially at right angles to the axis of said pin and a second pin disposed in said bore and removably and adjustably associated with said spindle and adapted to be projected beyond the surface thereof and into engagement with one of said apertures and said groove, said second pin having an internally screw-threaded bore in the outer end thereof and a plug having screw-threaded engagement with the bore of said spindle and having an externally threaded shank for engagement with the threaded bore of said pin.

10. In a device of the character described, the combination with a supporting member having a frusto-conical external surface which in axial section presents right angularly disposed surface elements, of a member to be rotatably supported thereby and having a correspondingly formed internal surface, a pin projecting at right angles to the surface of said supporting member and adapted to engage an annular channel formed in the said frusto-conical internal surface and a second pin removably associated with said supporting member and likewise adapted to engage in said annular channel, whereby to prevent separation of said members.

11. A roller boring drill head composed of a single piece including two integral downwardly projecting legs diametrically opposite each other, frusto-conical spindles formed on said legs and whose axes are inclined downwardly and inwardly and whose surface elements are approximately at right angles to each other so that the lowermost portion thereof forms a line approximately horizontal to the vertical axis of the bit head while the innermost portion thereof forms a line approximately parallel with the vertical axis of the bit head, a locking element projecting downward from the surface of each of said spindles, and each of said spindles having a lateral aperture, a removable locking device carried in each said aperture and adapted to be projected beyond the surface of the spindle, bushings having frusto-conical internal and external surfaces and adapted for engagement with said spindles, said bushings having apertures through which said locking elements are adapted to project and frusto-conical roller cutters each having an internal frusto-conical surface for

engagement with said bushings and having an annular groove into which said locking elements extend.

12. In a device of the character described, 5 a bearing member having an external frusto-conical bearing surface, a frusto-conical cutter having an internal frusto-conical surface adapted for engagement with the external surface of said bearing member, the opposed 10 surface elements thereof being disposed at approximately right angles to each other whereby the lowermost portion forms a line substantially horizontal to the vertical axis of the bit and the innermost portion thereof 15 forms a line substantially parallel with the vertical axis of the bit, and means passing through the frusto-conical portion of said bearing member, and engaging said cutter for permitting relative rotation of said cutter 20 and bearing members and preventing axial separation thereof.

13. The combination called for in claim 12, in which at least one of the means passing through the bearing member is removable.

25 14. In a device of the character described, the combination with a drill head, of a frusto-conical spindle secured thereto, a bearing element having internal and external frusto-conical surfaces and a frusto-conical roller 30 cutter having an internal frusto-conical surface, the internal surface of said bearing element being adapted for engagement with the frusto-conical spindle and the external surface of said bearing element having engagement 35 with the internal surface of said cutter, the internal surface of said cutter having an annular groove formed therein, and means projecting from said spindle through said bearing element and into said annular groove 40 for maintaining said cutter bearing and spindle in assembled relation.

15. In a device of the character described, a bearing member having an external frusto-conical bearing surface, a frusto-conical cutter having an internal frusto-conical bearing surface adapted for engagement with the external surface of said bearing member, the internal frusto-conical surface of said cutter member having an annular groove formed 50 therein, and means passing through said bearing member and engaging said cutter for permitting relative rotation of said cutter and bearing member but preventing axial separation thereof.

55 16. In a device of the character described, the combination with a drill head, of a frusto-conical spindle secured thereto, a bearing element having internal and external frusto-conical surfaces and a frusto-conical roller cutter having an internal frusto-conical surface, the internal surface of said bearing element being adapted for engagement with the frusto-conical spindle and the external surface of said bearing element having engagement 60 65 with the internal surface of said cutter, and

a member integral with said spindle projecting therefrom through said bearing element and into engagement with said cutter for maintaining said cutter, bearing and spindle in assembled relation.

17. In a device of the character described, 70 a bearing member having an external frusto-conical bearing surface, a frusto-conical cutter having an internal frusto-conical bearing surface adapted for engagement with the external surface of said bearing member, and a member passing through the frusto-conical surface of said bearing member, normal to an element thereof, and engaging said cutter for permitting relative rotation of said cutter 80 and bearing member but preventing axial separation thereof.

In testimony whereof I affix my signature.
EARL A. REED.
